US00D429655S

United States Patent [19]

Cowan et al.

[11] Patent Number: Des. 429,655

[45] Date of Patent: ** Aug. 22, 2000

[54] ELECTRIC METER COVER

[75] Inventors: **Peter C. Cowan**, Sidney; **Markus F. Hirschbold**, Victoria; **Werner Reinhard Simbeck**, Mill Bay; **I. Ross Macfarlane**, Victoria, all of Canada

[73] Assignee: **Power Measurement Ltd.**, Canada

[**] Term: 14 Years

[21] Appl. No.: 29/109,153

[22] Filed: Aug. 9, 1999

[51] LOC (7) Cl. 10-04

[52] U.S. Cl. D10/99; D10/103

[58] Field of Search D10/99, 100, 103; 174/17; 324/146, 149, 156, 115, 119, 110

[57] CLAIM

The ornamental design for an electric meter cover, as shown and described.

DESCRIPTION

FIG. 1 is a right front perspective view of the electric meter cover of the invention;

FIG. 2 is a front elevation of the electric meter cover illustrated in FIG. 1;

FIG. 3 is a top view thereof;

FIG. 4 is a left side view thereof;

FIG. 5 is a right side view thereof;

FIG. 6 is a bottom view thereof; and,

FIG. 7 is the rear end view thereof.

CERTIFICATE OF CORRECTION

PATENT NO. : Des 429,655
DATED : August 22, 2000
INVENTOR(S) : Peter C. Cowan et al.

Page 1 of 1

It is certified that error appears in the above-identified patent and that said Letters Patent is hereby corrected as shown below:

Title page, column 1

Line 1, under "U.S. PATENT DOCUMENTS", delete "Quellette" and substitute -- Ouellette -- in its place.

Column 2

Lines 9-10, delete "American National Standard for Electric Meters-Code for Electricity Metering,"".

Line 17, delete "Accuracy" and substitute --Accuracy -- in its place.

Line 21, insert -- "7700 ION® 3-Phase Power Meter Analyzer and Controller, *Power Measurement*, brochure, revised 12/8/98, first published 3/31/95. --.

Line 5, delete "Commision" and substitute -- Commission -- in its place.

Line 9, delete "Flickemeter" and substitute -- Flickermeter --.
